UNITED STATES PATENT OFFICE

JOHN W. O'DONNELL, OF SALEM, MASSACHUSETTS, ASSIGNOR TO THE TURNER TANNING MACHINERY COMPANY, OF PORTLAND, MAINE, A CORPORATION OF MAINE

MACHINE FOR OPERATING UPON HIDES, SKINS AND LEATHER

Application filed February 1, 1929. Serial No. 336,897.

This invention relates to machines for operating upon hides, skins and leather and is illustrated as embodied in a machine for setting heavy leather. It is to be understood, however, that the invention and various important features thereof may have other applications and uses.

Machines for setting leather, as heretofore constructed, have practically invariably been provided with a bed roll having a relatively firm, smooth-surfaced rubber covering, the bed roll serving to back the work while the latter is being operated upon by a bladed cylinder. For co-operation with the bed roll in feeding the work there has usually been provided a brass roll or a roll covered with a layer of hard rubber. While this construction has proved to be satisfactory as a general rule, there is a tendency for the work to move laterally to or beyond one end of the bed roll where it would be damaged, and in certain classes of work a feeding means of greater or more certain tractive power would be distinctly advantageous. In unhairing operations also, the slippery condition of the hide or skin has made it difficult to secure feeding of the work at a uniform speed without employing a plurality of feed rolls, or a brass feed roll with a fluted surface which may in some cases leave marks on the grain surface of the hide or skin.

In copending application Serial No. 151,772, filed November 30, 1926, in the name of G. A. Schettler, the difficulties mentioned above have been overcome by a novel construction and arrangement of spirally-bladed feed rolls which provide all the tractive power necessary in machines for operating upon hides, skins, and leather, and at the same time they secure straight-line feeding of the pieces of work whereby the tendency of work to shift laterally is prevented. It is an object of this invention to provide a simpler and somewhat less expensive means for accomplishing the results mentioned and thus be able to offer a good substitute construction having advantages in other directions, especially in the feeding of hides and skins in which the thickness dimension varies con-

siderably in different portions of the same piece of work.

To these ends, and in accordance with an important feature of the invention, there is provided in the illustrated machine, a bed roll having an outer layer or covering of an intimate mixture of rubber and rough fiber, such as wool, vulcanized together. The surface of the wool-rubber layer has a greater frictional quality than that of any other feed or bed roll now in commercial use having an even surface, that is, one free from projections, ribs or corrugations. Preferably, the compound comprises 27½ pounds of wool to 35 pounds of rubber, so that the proportion is approximately 1 pound wool to 1½ pounds rubber. It is to be understood, that this proportion may be varied considerably in accordance with the machine in which the bed roll is to be used and to suit conditions which vary with the kind of work to be performed. Preferably, too, and as shown, the surface layer of wool and rubber has a backing of relatively soft rubber between it and an iron core or shaft, so that the surface of the bed roll may yield to inequalities in the work. To prevent side-slipping of the work, that is, slipping toward or off one end of the bed roll, the relatively soft rubber layer is disposed throughout all the middle portion of the roll but terminates a substantial distance short of each end of the roll. In other words, the relatively firm layer of wool and rubber is thicker at each end of the roll and much less yielding than it is where backed by the relatively soft rubber layer. This arrangement prevents the lateral slipping of the work which tends to remain on the yielding portion of the roll. In the illustrated construction a binder layer of hard rubber is vulcanized to the rigid shaft of the roll and to this binder layer the soft rubber layer is fixedly secured during the vulcanization of the latter. Also the outer layer of mixed wool and rubber is firmly secured to the soft rubber layer and to the end portions of the binder layer during the vulcanizing operation, the construction and arrangement being such that the layers are successively ap-

plied and are secured to each other in a single vulcanizing operation.

For co-operation with the bed roll having a covering of the described wool-rubber composition, there is provided in the illustrated setting machine a feed roll having a wool-rubber layer or covering for co-operation with the bed roll in insuring perfect feeding of the hides or skins under all conditions.

Preferably, and as shown, this feed roll is covered with a wool-rubber composition in a layer of uniform thickness throughout, no soft rubber backing being used as in the case of the bed roll, since the latter provides the necessary yielding surface which accommodates variations in the thickness of the work. It is to be noted too that the illustrated rolls are especially well adapted to feed small skins and light leathers because of their even, uniform surfaces.

These and other features of the invention and novel combinations of parts will now be described in detail by reference to the accompanying drawings, and then pointed out more particularly in the claims.

In the drawings,

Fig. 1 is a longitudinal sectional view of a bed roll of improved construction;

Fig. 2 is a similar section of an improved feed roll; and

Fig. 3 is a transverse vertical section of a setting machine illustrating application of the invention to a special machine.

In the illustrated machine which is designed specially for the setting of hides, there are shown a bed roll 10 and a feed roll 12 arranged in co-operative relation to feed a piece of work 14 while it is being operated upon by bladed cylinders 16 and 18 of the usual construction in which the blades are helically arranged in sets extending in opposite directions from points between the ends of the cylinder.

Preferably, and as shown in Figs. 1 and 3, the bed roll 10 comprises an inner core of cast iron 20 upon a shaft 21. Upon the core 20 is a binder layer 22 of hard rubber about $\frac{1}{8}$ of an inch thick. Surrounding the binder layer for the greater portion of the length of the bed roll is a layer of relatively soft rubber 24 approximately $\frac{5}{8}$ of an inch thick. Preferably and as shown, this soft rubber layer terminates short of the ends of the bed roll. For example, in a roll 65 inches long the soft rubber layer stops five inches from each end of the core and hence is fifty-five inches long. Outside of the soft rubber layer 24, covering it and the binder 22 at the ends of the bed roll, is a layer 26 of wool and rubber composition, the wool being intimately and substantially uniformly intermixed with the rubber and the latter vulcanized to produce a relatively firm layer. Preferably the compound comprises 27 $\frac{1}{2}$

70 pounds of wool to 35 pounds of rubber so that the proportion is approximately one pound of wool to one and one-half pounds of rubber. It will be readily understood, however, that this proportion may be varied considerably in accordance with the machine in which the bed roll is to be used and with full allowance for the kind of work to be performed. The density of this layer is ordinarily from 115° to 125° plastometer on a 75 1250 needle.

75 The feed roll, shown in detail in Fig. 2, comprises a binder layer 30 upon a cast iron core 32, mounted upon a shaft 34, and surrounding the binder layer is a wool-rubber 80 layer 36 which extends the full length of the roll and is similar in composition and in frictional quality to the wool-rubber layer 26 of the bed roll 10, there being no soft rubber layer in the feed roll corresponding to the 85 layer 24 of the bed roll.

90 The wool-rubber composition provides a surface on the work feeding rolls which is even, or smooth in the ordinary acceptance of that term, since it has no projections, serrations, ribs or corrugations, such as are ordinarily employed to increase the gripping effect of feed rolls. Nevertheless the surface provided by the relatively smooth wool-rubber layer has a very marked frictional 95 factor, so much so, that the tractive effect is greatly increased over the smooth rubber rolls of prior constructions. The bed roll 10 in addition to the feature of a highly effective feeding surface has the advantage of 100 keeping the work disposed properly between the ends of the roll. This is due to the arrangement of a yielding portion throughout most of the length of the roll and relatively unyielding portions at each end thereof. 105 Because of this construction the pieces of work do not shift laterally to or beyond the ends of the roll.

110 Having described my invention, what I claim as new and desire to secure by Letters Patent of the United States is:

115 1. In a machine of the class described, a work contacting member comprising a rigid body portion, and a covering layer consisting of an intimate and substantially uniform mixture of wool and rubber vulcanized together to provide a frictional surface for engagement with a piece of work.

120 2. In a machine of the class described, a cylindrical member comprising a shaft, and a layer of a substantially uniform mixture of wool and rubber vulcanized together and secured to the shaft, the surface of the wool and rubber layer having a marked frictional quality adapting it for frictional engagement with a piece of work.

125 3. A roll for leather working machines, comprising a shaft, and a sleeve or covering for the shaft consisting of an intimate mixture of wool and rubber vulcanized together 130

to provide a frictional surface for effective feeding of hides, skins, and pieces of leather.

4. A roll for leather working machines comprising a shaft, a binder layer vulcanized upon the shaft, a soft rubber layer upon the binder layer, and a layer of wool and rubber vulcanized together and arranged exteriorly to the soft rubber layer, the wool and rubber layer serving to provide a frictional surface 10 for engagement with a piece of work.

5. A roll for leather working machines, comprising a shaft, and a sleeve or covering for the shaft, consisting of a mixture of wool and rubber in the proportion approximately 15 of one pound of wool to one and a half pounds of rubber, the rubber and wool being vulcanized together to provide a relatively firm wool-rubber layer having a frictional surface effective for the feeding of hides, skins 20 and pieces of leather.

6. A bed roll for leather working machines, comprising a shaft, a layer of soft rubber covering all the intermediate portion of the shaft and terminating a short distance from 25 each end of the shaft, and a sleeve or covering of a wool-rubber composition extending the full length of the bed roll, the construction and arrangement being such that the sleeve or covering of wool-rubber is backed 30 by the soft rubber layer throughout the greater portion of the length of the bed roll and is relatively unyielding at each end of the roll where the soft rubber layer is absent.

7. A roll for leather working machines, 35 comprising a shaft, a hard binder layer of rubber vulcanized on the shaft, a layer of relatively soft and yielding rubber vulcanized upon the binder layer, the soft rubber layer terminating a substantial distance short of 40 each end of the binder layer, and a relatively firm layer of wool and rubber intimately mixed and vulcanized together, the wool and rubber layer being vulcanized to the soft rubber layer and to the binder layer beyond the 45 ends of the soft rubber layer whereby the wool-rubber layer has thicker portions at each end of the roll and an intermediate thinner portion backed by the yielding soft rubber layer.

8. A bed roll for leather working machines, 50 comprising a metal core, a binder layer upon the metal core, a soft rubber layer upon the binder layer covering all of the middle portion of the binder layer and extending to within a short distance of each end of the binder layer, and a relatively firm wool-rubber layer covering the soft rubber layer and the binder layer beyond the soft rubber 55 layer at each end of the core, the construction and arrangement being such as to provide a frictional feeding surface on the bed roll throughout the length of the latter, the wool-rubber layer yielding to accommodate variations in thickness of the work where it is 60

backed by the soft rubber layer and being unyielding at the ends of the roll where the soft rubber layer is absent.

9. A roll for leather working machines having a frictional surface provided by a covering layer of an intimate mixture of wool fiber and rubber vulcanized together. 70

10. A roll for leather working machines, comprising a shaft, a layer of soft rubber covering all the intermediate portion of the shaft and terminating a short distance from each end of the shaft, and a sleeve or covering of a relatively firm rubber composition extending the full length of the roll, the construction and arrangement being such that the sleeve or covering of relatively firm rubber composition is backed by the soft rubber layer throughout the greater portion of the length of the roll and is relatively unyielding at each end of the roll where the soft rubber 75 layer is absent. 80

11. In a setting machine, a bed roll comprising a metal core, a soft rubber layer covering all the intermediate portion of the core and extending to within a short distance of each end of the core, and a sleeve or covering of relatively firm vulcanized rubber and wool composition providing a frictional surface for feeding pieces of work, said vulcanized composition being arranged over the soft rubber layer and over portions of the core beyond the soft rubber layer to provide end portions of the bed roll more unyielding than the intermediate portions of the bed roll, in combination with a bladed cylinder for operating upon a piece of work backed by the bed roll, said cylinder having blades helically arranged and extending in opposite directions from points between the ends of the cylinder, and a feed roll for co-operation with the bed roll in feeding the work past the cylinder, the relatively unyielding ends of the bed roll serving to counteract the tendency of the helically arranged blades to displace the work. 90 95 100

12. In a setting machine, a bed roll comprising a metal core, a soft rubber layer covering the core and extending to within a short distance of each end of the core, and a sleeve or covering of relatively firm vulcanized rubber and wool composition providing a frictional surface for feeding pieces of work, said vulcanized composition being arranged over the soft rubber layer and over portions of the core beyond the soft rubber layer to provide end portions of the bed roll more unyielding than the intermediate portions of the bed roll, in combination with a helically bladed cylinder for operating upon a piece of work backed by the bed roll, and a feed roll for co-operation with the bed roll in feeding the work past the cylinder, the relatively unyielding ends of the bed roll serving to counteract the tendency of the helically arranged blades to displace the work and said 105 110 115 120 125 130

feed roll having a covering of vulcanized rubber and wool to provide a frictional surface for co-operation with the bed roll in feeding the work.

⁵ In testimony whereof I have signed my name to this specification.

JOHN W. O'DONNELL.
